ELECTRONIC COMPARATOR OR THE LIKE

Richard E. Roeger, Mayfield Heights, Ohio, assignor to Cleveland Instrument Company, a corporation of Ohio

Application March 28, 1952, Serial No. 19,083

Term of patent 14 years

(Cl. D52—1)

To all whom it may concern:

Be it known that I, Richard E. Roeger, a citizen of the United States, residing at Mayfield Heights, in the county of Cuyahoga and State of Ohio, have invented a new, original, and ornamental Design for an Electronic Comparator or the like, of which the following is a specification, reference being had to the accompanying drawing, forming a part thereof.

The figure is a perspective view of an electronic comparator or the like, embodying my new design.

The characteristic features of the design reside in the solid line portion.

I claim:

The ornamental design for an electronic com-

parator or the like, substantially as shown and described.

RICHARD E. ROEGER.
